PARKING METER AND COIN SLOT
THEREFOR

Walter J. Herschede, Cincinnati, William Foy Herschede, Forestville, and William N. Woodruff, Cincinnati, Ohio, assignors to International Vehicular Parking, Ltd., a corporation of Delaware

Application March 10, 1942, Serial No. 434,138, now Patent No. 2,433,453, dated December 30, 1947, which is a division of application Serial No. 210,504, May 27, 1938, now Patent No. 2,289,838, dated July 14, 1942. Divided and this application May 1, 1945, Serial No. 591,306

5 Claims. (Cl. 161—15)

1

This application for patent is a division of our copending application Serial No. 434,138, filed March 10, 1942, now Patent No. 2,433,453, dated December 30, 1947, entitled Parking meter and coin slot therefor, which in turn is a division of Patent 2,289,838 of July 14, 1942, and the invention relates to parking meters of the general character adapted for mounting or positioning at intervals along roadways or streets, and which include timing mechanism and coin-controlled apparatus cooperating with the timing mechanism, for initiating operation of the timing mechanism of the parking meter.

An object of the invention is to provide timing mechanism in conjunction with a coin slot, of such character and structure that same may be handled as a unit in mounting and demounting same in a suitable housing provided for receiving and protecting the said mechanisms from the elements and the curious persons who might otherwise tamper therewith.

Another object is to provide a device of the character indicated, in which the various parts, when inactive, are relieved of all stress or strain attributable to the use of a clock spring or the equivalent therewith, for use as motive power.

These and other objects may be attained by the means described herein and illustrated in the accompanying drawings, in which:

Fig. 1 is an elevational view showing one side of a device embodying the invention and mounted on a customary standard.

Fig. 2 is an enlarged fragmental sectional view on line 2—2 of Fig. 1, showing the front wall only.

Fig. 3 is an enlarged fragmental sectional view of the device showing the rear wall only.

Fig. 4 is an elevational view of the clock mechanism disposed within the casing, and showing that side thereof that is exposed at that portion of the housing shown in Fig. 1, when the detachable door or panel, shown in Fig. 1 is removed.

Fig. 5 is a view of the mechanism shown in Fig. 4, but observed from the rear thereof, part of the coin slot mechanism having been removed.

Fig. 6 is an enlarged plan view of the device shown in Fig. 5, parts being omitted.

Fig. 7 is a fragmental end elevational view of parts shown in Fig. 4.

Fig. 8 is a perspective view of the mechanism shown in Fig. 6, parts being omitted.

Like reference characters denote like parts throughout the several views of the drawings.

Considering now more particularly a device

in accordance with our invention, attention is directed to the drawings. In referring to parts of the device (see Figs. 1, 2 and 3), reference will be made to the face 30 of the casing or housing 31 as the front of the device and the opposite outer face 32 thereof will be referred to as the rear of the device. Such terminology is used merely for facilitating description and not for the purpose of limitation, particularly so because to some persons it might appear that the face 30 should properly be called the rear or back of the device.

A large opening 33 (Fig. 1) is provided in the front face or wall 30, for which a removable door 15 or panel 34 is provided. Access to the interior of the casing, by way of the said large opening 33, permits access to the instrumentalities that control attachment and detachment of a coin slot cover plate 35 (see Fig. 3) which serves as a 20 detachable closure or panel for the opening 36 in the rear face or wall 32 of the housing 31. The detachable panel or plate 35 permits ready access, to authorized persons, to the coin slot mechanism for servicing same as may be necessary from time to time by reason of introduction of articles and substances, other than coins, 25 into the coin slot mechanism and which may interfere with proper functioning of the coin slot mechanism. A detailed explanation of the 30 mounting of the coin slot cover plate will be given later.

The front wall of the housing, in addition to said large opening 33, is provided with a smaller opening 37 for which a hinged door 38 is provided. The hinged door controls access to the lower portion of the internal chamber 45 in the housing and in which section of the internal chamber, the coins are collected and from which an authorized person may remove same, without disturbing any other parts of the device. Suitable lock controlled means are provided at 39 and 40 for controlling access by way of the panel 34 and door 38, to the interior of the housing or casing 31. Suitable bolts 41 and 42, associated with customary drums of key controlled tumbler type locks, are provided for bolting or locking the panel and door to the casing wall adjacent such panel and door.

Windows 63 and 64 (see Figs. 1 and 3) are provided at the front and rear of the device, and through each of which a signal device or flag 65, 66 is observable. The one window is provided in the panel 34 and the other is provided in the 50 casing wall. The signals are adapted to cooperate

with various other parts of the meter mechanism in a manner, for purposes explained later.

A suitable shank 67 is formed at the lower end of the housing 31, whereby to permit mounting of the device on a suitable standard, in any suitable manner.

The meter mechanism comprises a clock mechanism which may be of any suitable construction. Essentially, it comprises a spring motor, an escapement and a suitable gear train. Means are provided whereby the clock mechanism may be rendered operative upon introduction of a proper coin or token into the device and also for rendering the clock mechanism inoperative after a determinable period of time, as well as for actuating the signals and signal operating parts from the clock motor.

The front and rear plates (Fig. 6) are held in spaced relation by customary means, for example, suitable studs such as 83, with which suitable screws 840 cooperate, in accordance with customary practice. The upper ends of the plates, at the outer corners thereof are secured to inverted T-shaped brackets 84 and 85 (see Fig. 4). The brackets serve as supports for the shaft or axle 86 for the signals 65 and 66. Each signal comprises a white plate or panel and a red plate or panel. These panels are so related and connected that while the signals may move about the horizontal axle or axis 86, the signal panels of identical color are exposed at the windows at the front and back of the casing. The plates or panels 87, 88, 89 and 90, are graduated to indicate periods of time, and are adapted to cooperate with an indicator 91 (see also Fig. 5), comprising a pair of fingers 92 and 93, for showing the elapsed time of meter operation (see Fig. 8). When the established period of parking time has elapsed, the red panels are moved to positions adjacent the fingers for visibly indicating that the parking time is being exceeded. At other times, during operation of the device, the white panels are positioned adjacent the fingers. This matter of two color signals and their operation, as generally related will be explained in more detail hereafter. It is in order, however, to state the movement of the signals on their axis is accomplished (see also Fig. 7) by means of linkage including a bracket 94 secured to axle or shaft 86 and link 95 having at its upper end a pivoted connection with bracket 94 in offset or eccentric relation to the axis of axle or shaft 86. The lower end of link 95 is connected with a lever 108, of suitable actuating mechanism, explained later (see Fig. 8), for synchronized operation of the signals with the other parts of the meter mechanism.

The spring motor winding stem 46 (see Figs. 4 and 6) is associated with the customary clock spring barrel, ratchet, etc., whereby the wound spring within the barrel 96 operates a gear train indicated generally at 97, the last element 81 of which is any one of various customary escapements, shown in detail in Fig. 4. Coupled with the gear train (see also Fig. 8) is a pair of gears 98 and 99. These gears 98 and 99 are mounted on the same shaft or axle 100 and are identical, except that one gear is loose on the shaft and the other is fixed to the shaft. The two gears 98 and 99 may be locked together and for that purpose there is provided an idler gear 101. The idler gear 101 is rotatably mounted on a pivoted lever 102, and falls into engagement with gears 98 and 99 under the action of gravity, the positioning of gear 101 and its supporting lever being actuated

from the motor train in a manner that will be explained. As exemplified herein, the gear 98 is fixed to shaft 100, as is also the gear 103. The gear 99, integral with gear 104 is loose or freely revolvable upon shaft 100, except when the idler gear 101 is in mesh with it, and at which time the gears 98 and 99 are locked for movement together. The gear 104 receives power from gear 105 in power train 97. The gear 103 (see Fig. 8) and the gear 98 are fixed to shaft 100. Gears 104 and 99 are fixed together on a hollow shaft rotatable on shaft 101. Gear 103 is engaged by the gear segment 106 carrying the indicator 91. A pin 107 (see Fig. 8), carried by gear segment 106, is adapted to actuate a lever 108 (see also Fig. 6) which is pivoted on the axle or shaft 109 and on which shaft the segmental gear 106 is fixedly mounted. The end of lever 108, remote from the end thereof that is adapted to contact pin 107, is pivotally connected to the link 95 of the signal (Figs. 4, 6 and 7). The said pivotal connection is effected by means of a bearing pin 110 carried by the angularly turned end 111 of lever 108 and the bearing pin extends through a suitable aperture in the link 95 and a cotter pin or the like inserted in the transverse aperture 112 in bearing 110 prevents separation of the link 95 and lever 108. The signal is weighted so that it will return, under the influence of gravity, to its normal position, in which the red panels are disposed at the windows in the device, a position signalling improper parking of a vehicle. The pin 107 is so positioned on the segmental gear, that in setting the indicator to initial position in actuating the device, the pin will actuate the lever for moving the signals so the white signal panels are disposed adjacent the windows. A pin 113 on the lever will be received by a spring actuated catch 114 to hold the white signal panels into position until released upon expiration of allotted parking time, as more particularly noted herein-after, the catch then controlling release of the signals so they may move under the influence of the weight associated therewith, for returning the signals to normal position.

The pin 113 carried by lever 108 is angular in cross-section, and is adapted to cooperate with a hook-like catch or holding member 114 (see also Figs. 6 and 8). The catch 114 is pivotally mounted between the front frame plate 71 and an intermediate plate 115 carried by the meter mechanism frame. The catch 114 is secured to a shaft 116, loosely journaled in the frame plates 71 and 115. Also secured to said shaft 116 is an arm 117 carrying a pin 118. The pin extends through an opening 300 in the frame plate 71 (see Fig. 4) and is acted upon by a lug 119 of the time adjustment plate 120 upon the indicator 91 reaching a point denoting the expiration of an allotted parking period. The associated arm 117 and catch 114 are then lifted to release pin 113 and permit upward movement of arm 110 and a consequent return of the red signals to signalling position, as appears more fully below. Plate 120 may be adjusted arcuately upon the shaft 109, to which shaft (Fig. 6) the indicator 91 and segmental gear 106 are fixed, in order to set the device for different parking periods, twenty minutes, as in front of banks, or one hour, as in most places where the meters would be located. The adjustment of the plate 120 is effected by means of an arcuate slot 121 in the plate 120, through which a set screw 122 extends, the set screw being threaded into a collar 123 secured to shaft 109. Suitable graduations 124 on the frame plate, co-

operate with pointer or index finger 125 on the adjustment plate 120, to mark the setting of the time interval between movement of the signals from abnormal or operating position, (proper parking of a vehicle), at which time the white panels are disposed at the windows, to normal or non-operating position (improper parking of the vehicle), at which time the red panels are so exposed or positioned.

The pin 118 (Figs. 6 and 8) is actuated by the lug 119 for turning the catch 114 on its axis, for releasing the pin 113, thus freeing the lever and the signals to respond to the gravity influence of the weighted signals. The spring 126, yieldingly holds the catch in position to receive and hold the pin 113. The spring also yieldingly urges the pin 118 toward the lug 119. The pin 118 and catch 114 are so related to one another and to the pin 113 and the lug 119, that only a limited arcuate movement of the catch and pin 118 is possible before one or the other of said members 114 and 118 contact either the pin 113 or lug 119. Movement of indicator 91 to an initial position is had through the action of the coil spring 127 and collar 128 mounted on shaft 109 to which indicator 91 and its gear 106 are rigidly secured. This resetting of the indicator under spring action is permitted by the free turning of gears 103 and 99 when the idler gear 101 is lifted, incident to initiating operation of the meter mechanism. Any suitable arrangement for attaining the indicated function may be employed. As shown herein, the coil spring 127 has its one end secured to shaft 109 (see Fig. 6) and its other end is anchored to the frame plate 71 by means of a pin 130. The spring 127 is wound or tensioned as the indicator is moved at timing rate under the influence of the main spring motor 96, acting through the gear train 103, 105 and gear segment 106.

The idler gear 101 (see Figs. 6 and 8) is the instrumentality which locks or joins the spring motor power train and the various parts, including the indicator 91, and which parts are interrelated and interdependent as previously explained. When the idler gear is released from its normal function of joining the gears 98 and 99, the indicator may be manually moved back and forth as desired in adjusting the device, and consequently, when, in the intended functioning of the device, the idler gear is moved to release or inoperative position, the indicator is free to respond to the action of the spring 127 and to cause such coaction of the various other parts, that the clock mechanism is rendered operative, the signals are actuated, etc., wherefore, the meter is set in operation for its intended purpose or function of timing the parking period for which a person is obliged to insert a proper coin into the device.

Momentary release of the idler gear is sufficient to accomplish the indicated conditioning of the device.

The release of the idler is accomplished by releasing the lever 102 (see also Figs. 4 and 5), so the force of the spring motor, operating through gear 99, will force the idler gear away from the gears 98 and 99, thus freeing the gear 98 and permitting the spring 127 to move the indicator and initiates operation of the escapement, as previously explained.

Returning now to a fuller discussion of the signals 65 and 66 of our device, attention is directed to Fig. 7 in which is shown a view of parts observed when looking at the right hand end of the structure shown in Fig. 4. The panels 88 and 90 of signals 65 and 66 respectively are red, while

panels 87 and 90 are white, for example. White panels 87 or 90 are disposed as shown in Fig. 7, when the parts are in abnormal or operating position, as the meter is operating for measuring the period of parking time. As such time, it is seen that these panels are disposed in vertical position adjacent the windows 63 and 64 respectively. Both red and white panels have identical calibrations for identical cooperation with the indicator fingers 92 and 93. The meter is preferably so set that upon expiration of the time limit, the red signal panels 88 and 89 displace the panels 87 and 90, respectively, however, the clock mechanism continues to operate for an additional period of time or allowed overtime period, for example, ten minutes, as shown herein. This arrangement defeats the complaint that the user of a parking space might offer to an arresting officer to the effect that the time limit had just expired and that the user had no opportunity of moving his vehicle or of purchasing more parking time.

The panels 88 and 89 are fixedly mounted on a pair of spaced brackets 520, fixedly mounted on shaft or axle 86. The panels 87 and 89 are pivotally attached to the lower edges of panels 88 and 90 respectively. The lower edges of panels 87 and 89 are pivotally connected to the lower ends of links 521 and 522 respectively. The upper ends of links 521 and 522 are pivotally attached to opposite ends of bracket 523, fixed to bracket 25 (see Fig. 4). A stop pin 524 (see Fig. 7), carried by bracket 523, serves as an abutment against which one of the brackets 520 may contact, when the signal is released to respond to the action of gravity upon the weight 525 associated with the signal.

As panel 88 is raised and panel 90 is lowered through tilting of support 520 by pulling of link 95, panel 87 is lifted into view in the position previously occupied by panel 88, and the panel 89 is swung out of view permitting its previous position to be occupied by panel 90. Panels 87 and 89, of course, are directly moved by the rigidly supported panels 88 and 90, respectively, from which they hingedly depend. The lower edges of panels 87 and 89 are properly positioned through the supporting links 521 and 522, respectively. Thus, as support 520 is tilted back and forth under the action of the weight 525 and link 95, panels 88 and 87 are brought into and out of view on one side 50 of the meter and panels 89 and 90 are respectively brought into and out of view on the other side of the meter.

The links 521 and 522, panels 87, 88, 89 and 90, and the various parts cooperating therewith are so proportioned and related that all the panels may assume vertical positions and the panels 87 and 89 may both assume horizontal positions in substantially the same plane, without interference with other parts of the device.

Summarizing the operation of our device, attention is particularly directed to Fig. 8, wherein is illustrated the particular relationship of certain working parts of the meter at the expiration of a predetermined parking period. It must be noted that indicator 92 is in extreme right position and with coil spring 127 wound tight on shaft 109. The clocking mechanism is locked from operation by lever 131 pressing escapement 132 into engagement with one of the pallets of escapement wheel 133; the lever 131 at the same time holding pendulum 135 in unbalanced position. It is to be noted further that catch 114, and pin 113 on lever 108 are disengaged and the signalling mechanism attached to bearing pin 110 through link 95 75 (Fig. 7) has fallen by gravity to lift the link and

rotate lever 108 in a clockwise direction about shaft 109. At this time, the red panels 88 and 89 of the signalling mechanism are exposed to view in windows 63 and 64 of the meter casing.

Clocking of a predetermined parking period is initiated from the meter position just described by inserting a suitable coin 203 in the meter coin slot. As the coin is forced through coin slot 114 by the coin door mechanism, it contacts arm 191 of floating trigger 182, causing the trigger to move rearwardly and upwardly against spring tension. While the coin door is open, lug 228 on the door is displaced to engage portion 227 of lever 225, thereby locking shaft 146 against rotation during upward movement of the trigger 182. During the rearward and upward trigger movement, trigger stud 197 contacts face 204 of pivotally mounted gate 201, forcing catch member 208 into engagement with holding pawl 210 pivotally mounted on the rear wall of block 177. Chamfered lower arm 202 of gate 201 accordingly is held above the base 199 of coin chamber 175, thus providing a lateral abutment for preventing lateral discharge of the coin from the chamber. The coin finally passes in the space between trigger arms 188 and 191. The trigger then moves forwardly under spring action, following the curvature of the coin. Meanwhile, the coin door closes and lug 228 accordingly is displaced over portion 226 of lever 225, thereby permitting limited rotation of shaft 146. At this time, stud 197 of the trigger raises arm 224 of lever 146 to turn shaft 146 in a clockwise direction.

Upon rotation of shaft 146, spring pressed lever 145 loosely mounted on shaft 146, is depressed by 35 lug 148 of arm 147. Pin 143 on lever 102, accordingly, is released, and idler gear 101 is moved back and out of engagement with gears 98 and 99. These two gears then are freed to relative movement and spring 127 drives pointer 91 to the 40 left, as seen in the drawing, whereupon shaft 109, segmental gear 106, gears 103 and 98, and shaft 100 are rotated, while gear 99 and gear 104 idle on the shaft.

As pointer 92 rotates to the left, arm 154 fixed to shaft 109 strikes pin 155 of detent 212, thereby moving pawl 210 and releasing catch 208 of gate 201. The gate 201 then returns to normal position and the coin falls laterally from coin chamber 175 and into the coin chamber 333 to a 50 position before window 331.

The timing adjustment plate 120 (see also Fig. 4) also turns with shaft 109 and lug 119 moves away from pin 118 permitting catch 114 to rotate in a clockwise direction, as seen in the drawing, under spring action to contact pin 113. When pointer 91 approaches its extreme left position, pin 107 on the segmental gear 106 strikes the right end of lever 108, causing the lever to rotate in a counterclockwise direction about shaft 109. By this movement, link 95 is pulled down (see Fig. 7) and the white panels 65 and 66 of the signalling mechanism are exposed to view in windows 63 and 64 of the meter casing, as more particularly indicated above. Latch 114 then moves over pin 65 113 to lock the white signals in position.

When pointer 91 reaches its extreme left position as seen in Fig. 8, a portion of the pointer (see also Fig. 4) strikes lever 131 of the escapement locking mechanism moving the lower end 70 134 of the lever away from escapement member 132 and into the detent 136. Pendulum 135, which as previously noted was held off-center, starts the clockwork motor. At this time, gear 101 on arm 102 has moved by gravity to engage 75

gears 98 and 99 and the clockwork mechanism operating through gears 104, 99, 101, 98 and segmental gear 106, drives the pointer 91 to the right to commence the timing operation.

When the allotted timing period has expired, and pointer 91 again is at extreme right position, as shown in Fig. 8, lug 119 rotating with shaft 109, contacts pin 118 causing catch 114 to release the pin 113, whereupon the red signals 88 and 89 come to view in windows 63 and 64 of the meter casing, as explained hereinbefore. Lug 119 forces pin 118 upward and detent 136 of lever 129 is raised, whereupon the lower end 134 of lever 131 moving under the tension of spring 137, forces escapement member 132 into engagement with one of the pallets of escapement wheel 133 to stop the clockwork, the pendulum 135 at the same time being locked in unbalanced position.

When the device is tripped by insertion of a coin into the coin slot during the clocking of a predetermined period, operation is the same as outlined above, except, of course, the white signals and their controlling lever 108, remain undisturbed and the clockwork continues to run while pointer 91 returns to initial left-hand position.

As many possible embodiments may be made of our invention and as many changes may be made in the embodiment hereinbefore set forth, it is to be understood that all matter described herein, or shown in the accompanying drawings, is to be interpreted as illustrative and not as a limitation.

We claim:

1. In a parking meter, the combination with a movably controlled indicator finger, of a pair of dissimilarly colored movable panels selectively movable adjacent the finger and having corresponding legends or factors for cooperating in similar manner with the indicator finger, whereby the finger may indicate identical factors on both panels, and metering means for operating the finger along said panels and for controlling selective positioning of the panels adjacent the finger.

2. In a parking meter, a pointer movable at timing rate, a pair of horizontally hinged panels selectively movable adjacent said pointer, and means vertically moving said panels upon setting said pointer to its initial timing position and placing said pointer and one panel in cooperation and reversing movement of said panels and placing pointer and other panel in cooperation upon expiration of a prescribed timing period.

3. In a parking meter, a pointer movable at timing rate, a pair of horizontally hinged panels selectively movable adjacent said pointer, means vertically moving said panels upon setting said pointer to its initial timing position and placing pointer and one panel in cooperation, means latching said moving means, and means releasing said latching means and reversing movement of said panels and placing pointer and other panel in cooperation upon expiration of a predetermined timing period.

4. In a parking meter, pivotally mounted pointer means having a pin adjacent the pivot thereof and an adjustable auxiliary pointer coaxially therewith, a pair of horizontally mounted panels selectively movable adjacent the indicating end of said pointer means, means contacted by the pin of said pointer means in setting the same and rotating said panels about their axis and placing one panel in cooperation with the indicating end of the pointer means,

means latching said pin-contacted means, and means actuated by the adjustable auxiliary pointer releasing said latching means and reversing movement of said panels and placing the other panel in cooperation with the indicating end of the pointer means upon said pointer means having reached a predetermined position in its travel.

5. In a parking meter, forked pointer means movable at timing rate, two pair of panels horizontally mounted within the confines of the forked portion of said pointer means and with one pair selectively movable adjacent one forked prong and the other pair movable adjacent the other prong, and means lifting one pair of panels and dropping the other pair upon setting said pointer means to its initial position thereby placing the lower panel of the one pair in cooperation with one prong of said pointer means and placing the upper panel of the other pair in cooperation with the other prong of said pointer means,

10

said means also dropping the lifted pair of panels and lifting the dropped pair of panels to thereby shift cooperation of the pointer to the other panels upon the pointer means having reached a predetermined position in its travel.

WALTER J. HERSCHEDE.
